UNITED STATES PATENT OFFICE

2,443,979

OPERATING MECHANISM FOR WASHING MACHINES

Louis E. Deloghia, Agawam, Mass., assignor to Perkins Machine and Gear Company, West Springfield, Mass., a corporation of Massachusetts

Application May 23, 1945, Serial No. 595,316

4 Claims. (Cl. 74—77)

1

This invention relates to improvements in operating mechanism for washing machines and the like.

The principal objects of the invention are directed to the provision of operating mechanism for washing machines wherein movements of the oscillatable shaft for the paddle thereof are controlled.

Mechanism of the type to which the invention relates is shown in U. S. Letters Patent No. 2,275,698 to Strauss et al. In such a construction an agitator shaft carries a wheel, a reciprocable driving member and said wheel have complementary co-acting faces so that the reciprocating member oscillates the wheel and thereby the agitator shaft through an angle according to the pressure applied to the reciprocating member.

In such a construction the angle of oscillation is varied by varying the pressure applied to the reciprocating member. Variations are desirable inasmuch as certain goods require less agitation than other goods or certain goods are injured by too violent agitation. Thereby to accommodate the degree or angle of oscillation to particular goods, the pressure applied to the reciprocating member is varied.

There is a tendency for the oscillating strokes of the agitating shaft to rotate around the axis of oscillation. That is to say, assume the angle of oscillation of the agitating shaft to be 75°, said shaft while it moves back and forth through this angle of 75° is gradually rotating around the axis of oscillation so that the paddle winds up the goods being washed which, of course, is injurious to the goods. This movement of the oscillating strokes around the axis of oscillation may be termed "creeping" and it is desired to prevent this creeping and thereby prevent the goods being washed from being wound around the agitator and its shaft. To that end, according to the novel features of this invention, means is provided to prevent this creeping of the oscillating strokes of the agitator shaft.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a partial inverted plan view of a washing machine tub having the operating mech-

anism of the invention associated therewith; Fig. 2 is a sectional elevational view on the line 2—2 of Fig. 1;

Figs. 3 and 4 are plan and side elevational views of one form of device for guiding and applying pressure to the reciprocating member of the mechanism.

Referring now to the drawings more in detail, the invention will be fully described.

10 A washing machine tub is represented by 6 which has a bottom wall 2. A casing for the operating mechanism is represented by 8 which is secured to the washing machine wall 2 in the usual manner and it has a cover 10 which may be secured thereto in any desired manner. A shaft 12 has its lower end journaled in the casing 8 and extends upwardly alongside the tub 6 for operating a wringer which is usually associated with a washing machine.

20 A motor 14 is mounted in a bracket construction 16 which is secured to the housing in a manner similar to that shown in U. S. Patent No. 2,274,950 to Croft. A shaft 20 of the motor is connected by a coupling 22 to a shaft 24 which is journaled in the housing 8. Said shaft 24 has a worm 26 fixed thereto which is in engagement with the worm wheel 28 fixed on the shaft 12. As the shaft 20 of the motor 14 is rotated the worm wheel 28 is rotated.

30 An agitator shaft 30 is journaled in the housing and extends upwardly through the lower wall 2 of the tub. A driven wheel 32 is fixed on the shaft 30 and a driving member 34 is pivoted at 36 to the worm wheel 28.

35 The driven member 32 and the free end 38 of the driving member are provided with complementary angularly disposed engageable faces as in the Strauss patent referred to. As the driving member 28 rotates, the member 34 is reciprocated back and forth. Accordingly as pressure is applied to the free end 38 of the driving member 34 the driven wheel 32 and the agitator shaft are oscillated. A pressure member 40 is provided which has a guide member 42 oscillatable therein. The member 42 is provided with a groove 44 in which the free end 38 of the member 34 is reciprocable.

An adjusting member 50 is rotatable in a bearing 52 and its inner end 54 is in threaded engagement with means 56 associated with the housing. A compressor member 58 on the inner end of the member 50 is provided and yielding pressure means 59 such as a spring is disposed between the member 58 and the member 40. As the member 50 is rotated in one direction

or the other, more or less pressure is applied to the member 40 and in that manner the driving member 38 is acted upon with more or less pressure to oscillate the driven member 32 and the agitator shaft 30 through a greater or less angle according to the pressure applied to said member 40.

When fine delicate fabrics are being washed, less pressure is applied to the driving member 38 than is the case with heavier fabrics to provide a less angle of oscillation of the shaft 30. The mechanism is so arranged and constructed that the wheel 32 and agitator shaft may be operated between zero angle and the maximum and is accomplished by applying more or less pressure to the driving member. This may be accomplished by other means than that shown.

Whatever the angle of oscillation of the wheel may be there is a tendency for the oscillations to rotate or creep around the axis of oscillation so that the goods being washed are wound up on the agitator. It has been discovered that creeping is eliminated when the point at which pressure is applied to the driving member is varied accordingly as the applied pressure is varied and this is accomplished by the following means.

A pinion 51 is fixed to the agitator shaft 30 and a gear 52 in mesh therewith is mounted for rotation on a stud 54. A yoke member 56 is mounted for swinging movements at 58 and it has inner faces 60. A screw member 62 has right and left hand threads at its opposite ends 64 and 66. One end such as 64 is in threaded engagement with the member 68 carried by the housing and its other end in threaded engagement with the pressure member 40. A collar 70 is fixed to the screw 62 and a link 74 has its opposite ends pivotally connected to the members 70 and 56.

As the yoke member 56 is swung in one direction or the other, the member 70 of the screw is swung in one direction or the other so as to turn the screw 62. As the screw 62 is turned in one direction or the other the member 40 is thereby moved. In this way the point at which pressure is applied to the end of the driving member is varied or is adjusted along the path of movement of the reciprocating driving member.

The creep of the angle of oscillation of the agitator shaft is likely to occur with various angles of oscillation which depend on the degree pressure applied to the driving member 38 but the creep is obviated by positioning the pressure member 40 in certain positions fore and aft and it is so positioned by oscillating or turning the screw 62.

A pin or stud 80 extends upwardly from the gear 52 which is adapted to engage the inner faces 60 of the member 56 under certain conditions so as to swing said member 56.

As the driving wheel 32 is oscillated back and forth by the driving member 38 through a greater or less angle of oscillation depending upon the pressure applied by the member 40, the pinion 51 oscillates so as to oscillate the gear 52. As the said gear 52 oscillates the pin 80 thereof is, of course, oscillated back and forth through an angle depending upon the angle of oscillation of the agitator shaft. Should the oscillations of the agitator shaft 10 start to creep around the axis of oscillation in one direction or the other the pin 80 brings up against a face 60 of the member 56 to swing it in one direction or the

other thereby through the link 54 moving the member 70 and turning the screw in one direction or the other.

This brings about a movement of the pressure member fore and aft or axially of the screw to shift the point at which pressure is applied to the driving member 38 and thereby to apply the pressure at a point at which the wheel 32 will not creep.

It has been found that with different degrees of pressure applied to the driving member 40 that said member 40 requires different positions fore and aft to eliminate the objectionable creeping and the adjustment of said member 40 is accomplished by the screw mechanism which is actuated by the member 56. So long as there is no creeping the gear 52 and thereby the stud 80 oscillates back and forth through a certain angle but as soon as there is a tendency of the oscillations to creep the said stud brings up against one or the other of the surfaces 60 of the member 56 to swing said member 56 and bring about an adjustment of the block 40.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Operating mechanism comprising in combination, an oscillatable shaft and an oscillatable driven member thereon, a driving member reciprocable back and forth, said members having complementary engageable faces whereby the former member may be oscillated through various angles by the latter accordingly as varying pressures are applied to the latter, a pressure member for applying various pressures to said driving member movable back and forth in parallelism with the path of movement of the driving member, and means to move said pressure member back and forth.

2. Operating mechanism comprising in combination, an oscillatable shaft and an oscillatable driven member thereon, a driving member reciprocable back and forth, said members having complementary engageable faces whereby the former member may be oscillated through various angles by the latter accordingly as varying pressures are applied to the latter, a pressure member for applying various pressures to said driving member movable back and forth in parallelism with the path of movement of the driving member, and means to move said pressure member back and forth operable by said oscillatable shaft.

3. Operating mechanism comprising in combination, an oscillatable shaft, a driven member on said shaft, a driving member oscillatable back and forth in a certain path, said members having complementary engageable faces whereby the driven member is oscillated through a certain angle accordingly as a certain pressure is applied to the driving member, a pressure member for applying pressure to the driving member movable back and forth in parallelism with said certain path for shifting the point at which pressure is

applied to the driving member, and means for moving said pressure member operable by said oscillatable shaft.

4. Operating mechanism comprising in combination, an oscillatable shaft, a driven member on said shaft, a driving member oscillatable back and forth in a certain path, said members having complementary engageable faces whereby the driven member is oscillated through a certain angle accordingly as a certain pressure is applied to the driving member, a pressure member for applying pressure to the driving member movable back and forth in parallelism with said certain path for shifting the point at which pressure is applied to the driving member, and

10

15

means operable by the said shaft for moving the pressure member back and forth accordingly as the angle of oscillation of said oscillatable shaft tends to move about the axis of oscillation thereof.
